UNITED STATES PATENT OFFICE.

FRANK C. BRENDZA, OF CLEVELAND, OHIO.

DESIGN FOR A BADGE, BUTTON, PIN, OR ARTICLE OF SIMILAR NATURE.

53,194.

Specification for Design.

Patented Apr. 15, 1919.

Application filed January 27, 1919. Serial No. 273,488. Term of patent 3½ years.

To all whom it may concern:

Be it known that I, FRANK C. BRENDZA, a citizen of the United States, residing at Cleveland, county of Cuyahoga, and State of Ohio, have invented a new, original, and ornamental Design for Badges, Buttons, Pins, or Articles of Similar Nature, of which the following is a specification, reference being had to the accompanying drawing, forming part thereof.

The figure is a plan view of an ornamental badge, button, or pin, showing my new design.

I claim:

The ornamental design for a badge, button, pin, or article of similar nature, as shown.

FRANK C. BRENDZA.
